UNITED STATES PATENT OFFICE

**GORDON E. ROEDDING, OF GRAND RAPIDS, MICHIGAN, ASSIGNOR TO GRAND RAPIDS
BRASS COMPANY, OF GRAND RAPIDS, MICHIGAN, A CORPORATION OF MICHIGAN**

DESIGN FOR A LATCH

Application filed May 27, 1931. Serial No. 40,004. Term of patent 3½ years.

To all whom it may concern:

Be it known that I, GORDON E. ROEDDING, a citizen of the Dominion of Canada, residing at No. 929 Grandville Ave. S. W., Grand Rapids, in the county of Kent and State of Michigan, have invented a new, original, and ornamental Design for a Latch, of which the following is a specification, reference being had to the accompanying drawings, forming a part thereof, in which:—

Figure 1 is a plan view of a latch showing my new design; and

Figure 2 is a side elevational view thereof.

I claim:

The ornamental design for a latch substantially as shown.

GORDON E. ROEDDING.
